UNITED STATES PATENT OFFICE

STEWART S. KURTZ, JR., OF MERION, PENNSYLVANIA, ASSIGNOR TO THE ATLANTIC
REFINING COMPANY, OF PHILADELPHIA, PENNSYLVANIA, A CORPORATION OF
PENNSYLVANIA

REFINING HYDROCARBON OIL

No Drawing.

Application filed January 23, 1931. Serial No. 510,847.

The present invention relates to the art of mineral oil refining, and has particular reference to the separation of crude petroleum or petroleum products into fractions of different chemical compositions while of approximately the same distillation range.

In accordance with my invention, crude petroleum or petroleum products, particularly oils of substantial viscosity, are separated into various fractions by means of fractional extraction with an aromatic cyanide, such as benzonitrile.

It is recognized in the art that mineral oils, such as petroleum, comprise essentially a mixture of hydrocarbons of various groups of homologous series or compounds, such for example, as paraffins of the general formula C_nH_{2n+2} , olefines of the general formula C_nH_{2n} , hydroaromatics and polymethylenes of the same empirical formula, and various other series of compounds of chain and/or ring structures in which the hydrogen to carbon ratio is less than the foregoing series. A large number of individual compounds of each series and of differing boiling points are present in petroleum.

The various types of crude petroleum, which are generally classified into three groups, namely, paraffin base, naphthenic or asphaltic base, and mixed base, contain the various series of hydrocarbons mentioned heretofore in different proportions. For example, in the paraffin base crude oils, such as those obtained from the oil fields of Pennsylvania, there is a relatively high proportion of hydrocarbons having a chain structure and a high hydrogen to carbon ratio, whereas in the naphthenic or asphaltic base crude oils there is a relatively large proportion of hydrocarbons having ring structures and a low hydrogen to carbon ratio. Mixed base crude oils, such as are obtained from the Mid-Continent oil fields, contain hydrocarbons in proportions intermediate these two extremes.

As the use of viscous petroleum oils is almost entirely physical, the above described chemical nature of those oils is important in reflecting certain physical characteristics.

The variance in the proportion of the dif-

ferent series of hydrocarbons in paraffinic, naphthenic, and mixed base oils is evidenced by the physical properties of the various oils, and particularly by the relationship of the specific gravity to the viscosity of one oil as compared with another. For example, oil from a Pennsylvania crude with a viscosity of 400 seconds Saybolt Universal at 100° F., will show a specific gravity at 60° F. of about 0.878, whereas an oil of corresponding viscosity produced from a naphthenic crude, as one from the Gulf Coast area, will show a specific gravity of about 0.933 at 60° F. The relationship between the viscosity and gravity indicates the degree of the paraffinic or naphthenic character of the oil.

If a given crude petroleum be distilled into successive fractions and the specific gravities and viscosities of the several fractions determined, it will be found that they conform to the general relationship:

$$G = a + \frac{1.0752 - a}{10} \log (V - 38)$$

in which "G" is the specific gravity at 60° F., "V" is Saybolt Universal viscosity at 100° F., and "a" is a constant known as the viscosity-gravity constant. Fractions from each of the different types of crudes have different viscosity-gravity constants. Such constants are lower for fractions of the paraffinic crudes than are the constants for fractions of the naphthenic crudes. An article entitled "The viscosity-gravity constant of petroleum lubricating oils" by J. B. Hill and H. B. Coats which will be found in volume 20, page 641 et seq., Industrial and Engineering Chemistry for June, 1928, explains the determination of the constant for several typical oils.

The viscosity-gravity constant is, therefore, an index of the paraffinicity or naphthenicity of an oil, since when a given crude is distilled and fractions thereof are collected, regardless of the fraction upon which the specific gravity and the viscosity are taken, when such specific gravity and viscosity are substituted in the formula and the viscosity-gravity constant determined, the constant will be substantially the same for each of the several fractions of the crude.

The viscosity-gravity constants of the viscous fractions for some of the typical crudes are as follows: Milltown (Pennsylvania) 0.8067, Burbank (Mid-Continent) 0.8367, 5 Guadalupe (Gulf Coast) 0.8635, Mirando (Gulf Coast) 0.9025.

These oils are increasingly paraffinic as the viscosity-gravity constants decrease.

I have found that oils containing both the 10 paraffinic series of hydrocarbons and the various naphthenic series may be fractionally extracted with a suitable solvent such as an aromatic cyanide, and more particularly benzonitrile. The various series of hydrocarbons possess a differential solubility in this solvent, the naphthenic compounds being more soluble therein than the paraffinic hydrocarbons. By means of extraction with benzonitrile, it is, therefore, possible to effect 15 a partial separation of the naphthenic compounds from the paraffinic, and to obtain from an oil containing both classes an oil which is much more paraffinic than the original oil, and one which is much more naphthenic. 20 By my invention, for example, it is possible to produce an oil of the quality normally obtained from Appalachian crudes from crudes of the mixed base type from the Mid-Continent area, and, conversely, to obtain 25 oils from mixed base crudes such as are normally obtained from the naphthenic oils of the Gulf Coast area.

In practicing my invention, I prefer to mix the oil fraction to be treated with a suitable 30 proportion of benzonitrile at a temperature sufficiently high that complete solution is effected and a homogeneous liquid obtained. I then cool the mixture to a temperature sufficiently low to cause a separation of the liquid 35 into a two layer system, the upper layer being a solution of a relatively small amount of benzonitrile in the more paraffinic portion of the oil, and the lower layer comprising a solution of the more naphthenic portion of 40 the oil in benzonitrile. Instead of this heating and cooling to effect extraction, I may simply agitate the mixture of liquid at normal 45 temperatures. Where substantial quantities of solid hydrocarbons belonging to the 50 true paraffin series C_nH_{2n+2} are present, these solids or waxes remain in the upper layer, and may cause it to be solid or semi-solid. Separation of the two layers is then 55 effected, for example, by decantation, and the benzonitrile removed from each of the separated oil layers by vacuum distillation or other means, thereby obtaining two oils of similar distillation ranges but of widely different physical characteristics and correspondingly different chemical compositions.

Before removing the benzonitrile from the upper and more paraffinic layer of oil obtained in the above described process, I may add a further quantity of benzonitrile, and repeat the process for an extraction of addi-

tional naphthenic bodies from the oil. The extraction may be repeated any desired number of times, thereby producing oils of progressively increasing paraffinicity as evidenced by a decreasing viscosity-gravity constant. In wax-bearing oils, the final undissolved product is a mixture of solid and liquid hydrocarbons. While the exact chemical compositions of these compounds are not known, it is probable that the liquid hydrocarbons are branched chain hydrocarbons of the paraffin series, whereas solid bodies are straight chain paraffin hydrocarbons. This product may be further separated into solid and liquid hydrocarbons by any of the well-known dewaxing processes, such as the cold settling process.

In many instances it will be found of advantage to dewax the oil prior to the extraction process, as this expedites the manual operation of the latter.

My invention will be further understood from the following example:

100 parts of a previously untreated distillate obtained from a Gulf Coast crude oil 90 and having a viscosity of 612 seconds Saybolt Universal at 100° F., a specific gravity of 0.9303, and a consequent viscosity-gravity constant of 0.874 was heated to approximately 25° C. with an equal volume of benzonitrile. The homogeneous liquid which resulted from this heating was cooled to 10° C., and allowed to settle, whereupon a two-layer system formed which consisted of an upper undissolved oil layer comprising 50 parts 100 of the mixture, and a lower benzonitrile dissolved layer comprising 150 parts of the mixture. After separation, the layers were each freed from benzonitrile by vacuum distillation. The benzonitrile dissolved fraction yielded 92 parts of benzonitrile and 58 parts of oil having a viscosity of 64.8 seconds Saybolt Universal at 210° F., a specific gravity of 0.9548, and a viscosity-gravity constant of 0.904. The undissolved fraction yielded 8 110 parts of benzonitrile and 42 parts of oil having a viscosity of 373 seconds Saybolt Universal at 100° F., a specific gravity of 0.8950, and a viscosity-gravity constant of 0.834.

115 From this example, it will be seen that by one benzonitrile extraction there has been obtained two oil fractions which are respectively higher in paraffinicity and naphthenicity than the original oil. By repetition of the extraction process upon the benzonitrile undissolved fraction, oils may be obtained 120 which are increasingly paraffinic, as evidenced by progressively decreasing viscosity-gravity constants.

125 It is evident that by use of my process I am practically independent of the particular nature of the crude oil, but may produce viscous oils of any required characteristics from practically any type of oil.

130 For example, I am able, by my process, to

produce from petroleum of a mixed base type such as would, on normal batch distillation, give a residuum of a viscosity of 150 seconds Saybolt Universal at 210° F. with a specific gravity of 0.928 or more, a lubricating stock with a viscosity at 210° F. of 150 seconds Saybolt Universal or more, and a specific gravity not higher than 0.910. This latter combination of properties is typical of cylinder stocks produced from Pennsylvania crude.

In extracting oils containing appreciable amounts of wax, the oil may be dewaxed, for example, by cold settling, prior to the extraction. The process is operable, however, in the absence of a preliminary dewaxing.

For brevity, in the appended claims, the term "benzonitrile" is employed in a generic sense to include that material and equivalent aromatic cyanides or mixtures thereof.

When herein and in the appended claims, an oil is specifically referred to as being "viscous", it is to be understood that the oil is of substantially viscosity, i. e., having a Saybolt Universal viscosity at 100° F., of the order of 50 seconds and upwards.

What I claim is:

1. In the art of refining mineral oils containing paraffinic and naphthenic hydrocarbons, the process which comprises bringing the oil into contact with benzonitrile, thereby effecting solution of a portion of the oil richer in naphthenic hydrocarbons in the benzonitrile, separating the benzonitrile solution of oil from the oil so treated, and removing the benzonitrile from each of the fractions so obtained, thereby to obtain fractions of the oil respectively richer in paraffinic and naphthenic hydrocarbons.

2. The process of separating mineral oils containing paraffinic and naphthenic hydrocarbons into fractions, which comprises bringing the oil into contact with benzonitrile, thereby effecting solution of a portion of the oil richer in naphthenic hydrocarbons in the benzonitrile, separating the benzonitrile solution of oil from the oil so treated, and distilling the benzonitrile from each of the fractions so obtained, thereby to obtain fractions of the oil respectively richer in paraffinic and naphthenic hydrocarbons.

3. In the art of refining mineral oils containing paraffinic and naphthenic hydrocarbons, the process which comprises bringing the oil into contact with benzonitrile, thereby effecting solution of a portion of the oil richer in naphthenic hydrocarbons in the benzonitrile, separating the benzonitrile solution of oil from the oil so treated, and retreating the treated oil with additional benzonitrile.

4. In the art of refining oils containing paraffinic and naphthenic hydrocarbons, the process which comprises adding benzonitrile to the oil, heating the mixture to such a temperature as to effect solution, cooling the solu-

tion to form a two layer system, and separating the upper layer from the lower layer.

5. In the art of refining mineral oils containing paraffinic and naphthenic hydrocarbons, the process which comprises adding benzonitrile to the oil, heating the mixture to such a temperature as to effect solution, cooling the solution to form a two-layer system, removing the lower layer, and similarly retreating the upper layer with benzonitrile.

6. The method of producing paraffinic lubricating oil from mixed base crude, which comprises distilling the crude and bringing a portion thereof into contact with benzonitrile, thereby partially dissolving the oil, separating the benzonitrile solution of oil from the oil so treated, and removing the benzonitrile from the treated oil.

7. The process of producing a lubricating stock of specific gravity less than .910 and of Saybolt Universal viscosity greater than 150 seconds at 210° F., from a crude petroleum which on normal distillation yields a residuum of 150 seconds Saybolt Universal viscosity at 210° F. and a specific gravity greater than .928, which comprises producing a residuum from the crude petroleum, and extracting said residuum from said crude petroleum with benzonitrile.

8. In the art of refining mineral oils containing paraffinic and naphthenic hydrocarbons, the process which comprises separating the oil into fractions respectively richer in paraffinic and naphthenic compounds by extracting said oil with benzonitrile.

9. In the art of refining mineral oils containing paraffinic and naphthenic hydrocarbons, the process which comprises fractionally extracting the oil with benzonitrile to produce fractions of the oil respectively richer in paraffinic and naphthenic compounds.

10. In the art of refining mineral lubricating oil containing paraffinic and naphthenic hydrocarbons, the step of fractionally extracting the oil with benzonitrile to effect a separation of fractions respectively richer in paraffinic and naphthenic compounds.

11. The process of producing a lubricating stock of specific gravity less than .910 and of Saybolt Universal viscosity greater than 150 seconds at 210° F., from a crude petroleum which on normal distillation yields a residuum of 150 seconds Saybolt Universal viscosity at 210° F., and a specific gravity greater than .928, which comprises separating a residuum from said crude petroleum and bringing such residuum into contact with benzonitrile, to effect solution of a portion thereof with benzonitrile, separating the benzonitrile solution of oil from the portion which does not dissolve therein, and removing the benzonitrile from the oil of said solution.

12. In a process for separating a viscous mineral oil containing paraffinic and naph-

thenic hydrocarbons into fractions which are respectively richer in naphthenic hydrocarbons and paraffinic hydrocarbons other than wax, the step which comprises extracting the oil with benzonitrile.

13. In a process for separating viscous mineral oil, liquid at ordinary temperatures, containing paraffinic and naphthenic hydrocarbons, into fractions respectively richer in paraffinic and naphthenic hydrocarbons, the step which comprises extracting the oil with benzonitrile.

14. In a process for separating a substantially wax free viscous mineral oil containing paraffinic and naphthenic hydrocarbons into fractions respectively richer in paraffinic and naphthenic hydrocarbons, the step which comprises extracting the oil with benzonitrile.

15. The process of treating a viscous fraction of a crude oil of one type containing paraffinic and naphthenic hydrocarbons to procure a fraction having the quality of a corresponding fraction of a crude oil of different type having a greater content of paraffinic hydrocarbons, which comprises extracting the viscous fraction with benzonitrile, and separating the oil so treated into portions respectively richer in paraffinic and naphthenic hydrocarbons.

16. The process of treating a viscous fraction of a mixed base crude oil to procure a fraction having the quality of a corresponding fraction of a paraffinic base crude, which comprises extracting the viscous fraction with benzonitrile, and separating the oil so treated into portions respectively richer in paraffinic and naphthenic compounds.

17. In the art of refining mineral oils, the process which comprises adding benzonitrile to a viscous oil, liquid at ordinary temperatures, containing paraffinic and naphthenic hydrocarbons, heating the mixture to a temperature sufficient to effect solution, cooling the solution to a temperature sufficient to form two layers respectively richer in naphthenic hydrocarbons and paraffinic hydrocarbons other than wax, and separating the upper layer richer in paraffinic hydrocarbons from the lower layer richer in naphthenic hydrocarbons.

18. In the art of refining mineral oils, the process which comprises adding benzonitrile to a viscous oil, liquid at ordinary temperatures, containing paraffinic and naphthenic hydrocarbons, heating the mixture to a temperature sufficient to effect solution, cooling the solution to a temperature sufficient to form two layers, separating benzonitrile and paraffin wax from the upper layer, and separating benzonitrile from the lower layer to produce one fraction richer in paraffinic and a second fraction richer in naphthenic hydrocarbons than said viscous oil.

65 In testimony whereof I affix my signature.
STEWART S. KURTZ, JR.

DISCLAIMER

1,899,969.—*Stewart S. Kurtz, jr.*, Merion, Pa. REFINING HYDROCARBON OIL.
Patent dated March 7, 1933. Disclaimer filed February 15, 1934, by the
assignee, *The Atlantic Refining Company*.

Enters this disclaimer, to wit:

Petitioner disclaims from the scope that the description in said patent gives to the claims of said patent, the process of extraction with benzonitrile (C_6H_5CN) of either a viscous mineral oil containing paraffinic and naphthenic hydrocarbons, or a viscous mineral oil liquid at ordinary temperatures and containing paraffinic and naphthenic hydrocarbons, to produce fractions respectively richer in naphthenic hydrocarbons and paraffinic hydrocarbons.
